[57] CLAIM

The ornamental design for a base station for a mobile communication network, as shown and described.

DESCRIPTION

FIG. 1 is a front and side perspective view of a base station for a mobile communication network showing my new design;

FIG. 2 is a rear and side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view of the base station from FIG. 1 without front cover and lower hatch open;

FIG. 10 is a rear perspective view thereof;

FIG. 11 is a front view of the front cover of the base station from FIG. 1; and,

FIG. 12 is a rear view thereof.

The base station and front cover therefor have been shown separately in FIGS. 9-12 for convenience of illustration.
